UNITED STATES PATENT OFFICE.

EDWARD J. FUTTERER, OF BUFFALO, NEW YORK.

MEANS FOR USE IN OPERATING ELECTRIC CARS AND THE LIKE.

Application filed January 31, 1922. Serial No. 533,136.

To all whom it may concern:

Be it known that I, EDWARD J. FUTTERER, a citizen of the United States, residing at Buffalo, in the county of Erie and State of New York, have invented a new and useful Improvement in Means for Use in Operating Electric Cars and the like, of which the following is a specification.

This invention relates to means for use in operating electric cars or other vehicles and more particularly to means for stopping the operation of the vehicle and actuating certain safety or emergency devices.

The objects of this invention are to provide means of this kind of improved construction which make it impossible to start or to continue the operation of the vehicle while the operator is engaged otherwise than in the operation of the vehicle; also to provide means of this kind which may be used for actuating a plurality of safety devices in case an accident appears imminent; also to improve the construction of means of this kind in other respects hereinafter specified.

In the accompanying drawings,

Figs. 1, 2 and 3 are elevations partly in section of a handle for actuating the operating means embodying the invention, and

Fig. 4 is a diagrammatic view showing the connections between the several devices to be operated and the actuating handle.

Briefly stated, the invention includes an auxiliary handle which may be mounted in any position where it is readily accessible, for example, on the air brake handle of the vehicle and which is so arranged that it normally moves into a position to cause the vehicle to stop, this being accomplished in the construction shown, by actuating a device for turning the controller or analogous device into an "off" position, also applying the brakes and opening the door or doors of the vehicle. The auxiliary handle, while the car is in operation, is held by the operator in a position in which the actuation of the brakes, controller off device and door opening device are rendered inoperative. The auxiliary handle may be so constructed, if desired, that in case of emergency this handle can be moved into a third position in which all of the devices for stopping the vehicle are actuated, as well as other emergency or accident preventing devices, such as an alarm, fender dropping means, track sanding mechanism and a circuit breaker trip. By means of this arrangement the

motorman or operator of the vehicle can instantly actuate the emergency devices without taking his hand from the air brake handle, and furthermore the device is particularly desirable in the case of one-man cars since the car cannot be started while the operator has his hand off of the auxiliary handle.

In the particular embodiment of this invention shown in the drawings, A represents the valve housing of an air brake valve which is provided with the usual valve stem a by means of which the air valve may be opened or closed for applying or releasing the brakes. The valve stem a may be turned by means of the usual air brake handle a'. All of these parts have heretofore been used in connection with electric cars and locomotives and of themselves constitute no part of this invention.

The auxiliary handle may be of any suitable or desired construction and, in the particular embodiment of the invention shown in the drawings, is mounted on the air brake handle a'. B represents the auxiliary handle and which, in the construction shown, is slidable lengthwise of the air brake handle a'. The auxiliary handle is preferably provided with an extension b which engages a part of the air brake valve and assists in guiding the auxiliary handle in its movement lengthwise of the air brake handle. The auxiliary handle is also provided with a cam projection C having a cam face c which is adapted to engage a slidable stem or part D arranged above the valve stem a, the cam being arranged to raise the stem or part D when the auxiliary handle is moved toward the axis of the air brake valve A.

In the construction shown, the auxiliary handle B is normally moved lengthwise of the air brake handle toward the axis of the air brake valve by means of a spring E surrounding the air brake handle a' and bearing at one end against an enlargement e at the end of the air brake handle, and at the other end on a part of the auxiliary handle B. This spring is preferably of such strength as to move the auxiliary handle to a position intermediate of its outer and inner positions.

When the auxiliary handle B is moved into its half way position by means of the spring E, the stem or part D is raised in such a manner that a switch or circuit closing member F mounted on the stem D en-

gages two contacts or terminals f f' so as to close a circuit. The stem D is guided in its movement by means of guide rods f^2 rigidly mounted on a part of the vehicle 5 (not shown), and a spring f^3 arranged about the stem D normally holds the circuit closing member F out of engagement with the contacts f f' . Consequently when the auxiliary handle B is held in its outer position 10 on the air brake handle a' the stem D and circuit closing device F occupy the positions shown in Fig. 1. The auxiliary handle is held in its outer position by the motorman or engineer while operating the vehicle and 15 while in this position the auxiliary handle may be used for actuating the air brake handle a' without actuating the stem D or parts connected therewith. If for any reason the motor man or engineer releases 20 the auxiliary handle B, the spring E will move the same into the position shown in Fig. 2, thus completing a circuit between the contacts f f' which will have the effect of applying the brakes, moving the controller to the off position, and opening the door or doors, as will be hereinafter explained.

Means are preferably provided whereby the auxiliary handle may actuate certain 30 emergency or safety appliances when positively moved by the operator into a third position, and in the construction shown, these means are arranged as follows:—

The upper end of the switch stem D is 35 adapted to engage an emergency air valve stem G which is preferably arranged in alinement with the switch stem D. The emergency air valve stem G is connected with a valve g arranged in a housing g' , and when the stem G is raised the air valve g is opened to permit air to pass through the valve housing. This housing in the construction shown, is connected by means of a pipe g^2 with a suitable air supply, and a 40 pipe g^3 connects to certain emergency or accident-preventing devices. The raising of the stem G of the emergency air valve can be accomplished by moving the auxiliary handle B toward the axis of the air brake 45 valve A, into the position shown in Fig. 3. The handle can only be moved into this position by a positive action on the part of the motorman or engineer, since the spring E is only of such strength to move the auxiliary handle approximately into the position 50 shown in Fig. 2. The emergency handle is moved into the position shown in Fig. 3 when the motorman or engineer wishes to actuate all of the emergency devices for 55 the purpose of preventing an accident, and by arranging the circuit closing stem D and the auxiliary valve stem G above the axis of the air brake valve A, the motorman or engineer retains full control of the application of the air brakes independently of 60 the car stopping and emergency devices, even after the auxiliary handle has been moved to its inner or emergency position.

Fig. 4 shows the connections between the various parts of the device. In this Figure the switch stem D and contact making device F are shown diagrammatically, and when these parts are in their circuit closing positions, current may flow from a suitable source of power (not shown) through a conductor h , which conductor includes the winding of an electromagnet H. When the current passes through the conductor h and the magnet coil H, the core h' of the magnet is raised to open an air valve I. The opening of this valve admits air to an air pipe i which is connected with a plurality of branch pipes i' i^2 i^3 which are connected with various devices for stopping a car. For example, in the case illustrated in the drawings, the branch pipe i' is connected with a suitable device for moving the controller or throttle valve into an off position, this device being shown diagrammatically at I' . The branch pipe i^2 connects with the 85 brake cylinder of the vehicle which is diagrammatically shown at I^2 , a check valve i^4 being inserted into this branch pipe for the reason that air may be admitted to the brake cylinder by means of the air 90 brake valve A and when air is so admitted the check valve i^4 prevents the air from flowing into the branch pipes i' and i^3 . The branch pipe i^3 connects with a door opening device represented diagrammatically at I^3 . Consequently, it will be seen that when the motorman or engineer releases his hold on the auxiliary handle B, air will be admitted to the controller off device, 100 brake cylinder and door opening device, so that the car or train will be stopped and will be in a position to receive and discharge passengers and will not start except by a positive action on the part of the engineer or motorman. This leaves the motorman or engineer free to collect fares or to perform any other work that may be desired. Furthermore, if during the operation of the car, the motorman or engineer should 105 for any reason release his hold on the auxiliary handle, the car or train will be brought to a stop, so that in case of accident to the engineer or motorman, or sudden sickness, the lives of the passengers are not endangered.

If the auxiliary handle B is moved into the emergency position, and the emergency valve g is opened, air is admitted into the pipe g^3 , which in the construction shown is adapted to actuate a plurality of emergency or accident preventing devices and preferably also actuate the several car stopping devices described. For this purpose, the pipe g^3 has a branch pipe K connecting with the pipe i and provided with a check 115 valve.

- valve k , so that air may pass from the pipe g^3 to the pipe i to actuate the car stopping devices to which the several branch pipes i^1, i^2, i^3 are connected, but the check valve 5 will prevent air from passing from the pipe i to the pipe g^3 . The branch pipe K and check valve k are preferably, though not necessarily, used and have the advantage of positively ensuring the admission of air 10 to all of the car stopping and emergency devices when the handle is moved into the emergency positions, the air being admitted through this check valve even though the flow of current to the car is interrupted. 15 The pipe g^3 is provided with a number of other branch pipes k^1, k^2, k^3 for actuating emergency or accident preventing devices. For example, the branch pipe k is shown 20 grammatically at K' which causes the fender to be dropped and an alarm to be actuated, and the branch pipe k^2 is connected with a sander device represented diagrammatically at K^2 . The branch pipe k^3 may be connected 25 to a device shown diagrammatically at K^3 for tripping the circuit breaker to interrupt the flow of current to the propelling motor or motors of the vehicle. Other branch pipes may of course, be used 30 if desired to operate additional emergency devices, or if desired, some of the emergency devices referred to may be omitted or replaced by other devices.

The construction described is very desirable for the reason that it is simple and comparatively inexpensive to construct and install and is very effective in bringing the vehicle to a positive stop in case the operator's hand releases the auxiliary handle, 40 and insures the stopping of the car until the auxiliary handle is positively withdrawn from its normal position. The device has the further advantage that it may be used to apply the emergency devices by an additional manipulation of the same auxiliary handle, and by mounting this handle on the air brake handle of the vehicle, the operator constantly has a grip on the auxiliary handle so that he need lose no time in 45 moving this handle to the emergency position and thus avoid accidents.

The invention has been described more particularly as intended for use on electric cars or trains, but it will be understood that 50 the invention may equally well be applied to steam or other locomotives or trains.

I claim as my invention:

1. Means for use in operating electric cars and the like, including devices for stopping the car and emergency devices, a handle which is adapted to be held by an operator in a position to operate the car, and means which act when said handle is released by the operator to normally move 60 said handle into a position to cause the actuation of said stopping devices, said handle being movable into a third position to cause the actuation of said emergency devices.
2. Means for use in operating electric 70 cars and the like, including devices for stopping the car and emergency devices, a handle which is adapted to be held by an operator in a position to operate the car, means adapted to cause the actuation of 75 said car stopping devices and which are actuated by said handle when released by the operator, and means for actuating said emergency devices and which means are placed into operation when said handle is 80 moved by the operator into a third position.
3. Means for use in operating electric 85 cars and the like, including devices for stopping the car and emergency devices, a handle which is adapted to be held by an operator in a position to operate the car, means adapted to cause the actuation of 90 said car stopping devices, and means for moving said handle when released by the operator into a position to engage said actuating means, said handle being movable into a third position to cause the actuation of 95 said emergency devices.
4. Means for use in operating electric 100 cars and the like, including devices for stopping the car and emergency devices, a movable handle which is adapted to be held by an operator at one end of its path of movement to operate the car, means for yieldingly 105 moving said handle into an intermediate position for actuating said car stopping devices, and means for actuating said emergency devices and which are actuated when said handle is moved to the other end of 110 its path of movement.
5. Means for use in operating electric 115 cars and the like, including devices for stopping the car and emergency devices, a movable handle which is adapted to be held by an operator at one end of its path of movement to operate the car, means for actuating said car stopping devices and which are arranged to be actuated by said handle when the 120 same is in an intermediate position, and means for actuating said emergency devices, said last mentioned means being placed into operation by said handle when the same is moved toward the other end of its path of movement.
6. Means for use in operating electric 125 cars and the like, including devices for stopping the car and emergency devices, a movable handle which is adapted to be held by an operator at one end of its path of movement to operate the car, means for actuating said car stopping devices, means for actuating said emergency devices, said means being so arranged relatively to the handle that both 130 of said means will be engaged by the handle

when the same is at the other end of its path of movement, and means for causing said handle when released by the operator to engage the actuating means for said car 5 stopping devices.

7. Means for use in operating electric cars and the like, including devices for stopping the car, a handle for use in operating the car, an auxiliary handle mounted on said 10 first mentioned handle and movable relatively thereto and adapted to be grasped by an operator to move said first mentioned handle, and means for normally moving said auxiliary handle in a direction to cause the 15 actuation of said car stopping devices.

8. Means for use in operating electric cars and the like, including devices for stopping the car and emergency devices, a handle which is used by the operator in controlling 20 the movement of the car, an auxiliary handle mounted on said first mentioned handle and movable relatively thereto, said auxiliary handle being adapted to be held by an operator in a position to operate the car, 25 and means which act when said auxiliary handle is released by the operator to normally move said auxiliary handle into a position to cause the actuation of said car stopping devices, said auxiliary handle being 30 movable into a third position to cause the actuation of said emergency devices.

9. Means for use in operating electric cars and the like, including devices for stopping the car and emergency devices, a handle 35 which is used by the operator in controlling the movement of the car, an auxiliary handle mounted on said first mentioned handle and movable relatively thereto, means for actuating said car stopping devices, means 40 for actuating said emergency devices, both of said actuating means being arranged in operative relation to said auxiliary handle, said handle being held by the operator out of engagement with said actuating means 45 when operating the car and being movable by the operator into a position to actuate both of said means, and means for moving said auxiliary handle into a position to engage said means for actuating said car stopping 50 devices when said auxiliary handle is released by the operator.

10. Means for use in operating electric cars and the like, including devices for stopping the car and emergency devices, an air 55 brake handle, an auxiliary handle movably mounted on said air brake handle and adapted to be held at one end of its path of movement while the car is being operated, a spring which normally moves said auxiliary handle into a position intermediate between the ends of its path of movement, means for actuating said car stopping devices, said means being so arranged with 60 respect to said auxiliary handle as to be actuated thereby when the auxiliary handle is 65

moved to an intermediate position by said spring, and means engaged by said handle when moved to the other end of its path of movement by the operator for causing the actuation of said emergency devices.

11. Means for use in operating electric cars and the like, including devices for stopping the car and emergency devices, a handle which is movable about an axis to control the operation of the car, an auxiliary handle 70 movable relatively to said handle and having a cam shaped portion movable relatively to said axis, a member extending into proximity to said axis and adapted to be moved by said cam into a position to actuate said car stopping devices, and a second member 75 adapted to be engaged by said first member after an initial movement of said first member, to move said second member into a position to cause the actuation of said emergency 80 devices.

12. Means for use in operating electric cars and the like, including devices for stopping the car, a handle which is movable about an axis to control the operation of the 90 car, an auxiliary handle movable relatively to said first mentioned handle and having a cam shaped portion movable relatively to said axis, a member extending into proximity to said axis and adapted to be engaged 95 by said cam shaped portion to cause the actuation of said car stopping devices, and a spring which normally holds said auxiliary handle in a position to engage said member, said auxiliary handle being held by the 100 operator against the action of said spring while operating the car.

13. Means for use in operating electric cars and the like, including devices for stopping the car and emergency devices, a handle 105 which is movable about an axis to control the operation of the car, an auxiliary handle movable relatively to said handle and having a cam shaped portion movable relatively to said axis, a member extending into proximity to said axis and adapted to be engaged 110 by said cam shaped portion to cause the actuation of said car stopping devices, and a spring which normally holds said auxiliary handle in a position to engage said member, said auxiliary handle being held by the 115 operator against the action of said spring while operating the car, and means for actuating said devices when said auxiliary handle is moved into a third position.

14. Means for use in operating electric cars and the like, including devices for stopping the car and emergency devices, a handle which is movable about an axis to control the operation of the car, an auxiliary handle 125 movable lengthwise of said handle and having a cam shaped portion adapted to move into various positions above said axis, said auxiliary handle being held in its outer position by an operator while operating the car 130

and movable inwardly to different positions to cause the operation successively of said car stopping devices and said emergency devices.

5 15. Means for use in operating electric cars and the like, including devices for stopping the car and emergency devices, a handle which is movable about an axis to control the operation of the car, an auxiliary handle

10 movable relatively to said handle and having a cam shaped portion movable relatively to said axis, a member extending into proximity to said axis and adapted to be engaged by said cam shaped portion to cause the actuation of said car stopping devices, and a

15 spring which normally holds said auxiliary handle in a position to engage said member, said auxiliary handle being held by the operator against the action of said spring

20 while operating the car, means for actuating said emergency devices when said auxiliary handle is moved into a third position, and a spring which normally holds said auxiliary handle in position to cause the actuation of

25 said car-stopping devices.

16. Means for use in operating electric cars and the like, including devices for stopping the car and emergency devices, a handle which is movable about an axis to control

30 the operation of the car, an auxiliary handle movable relatively to said handle and having a cam shaped portion movable relatively to said axis, and actuating members adapted to actuate said car stopping devices and said

35 emergency devices and extending into proximity to said axis and to be successively moved by said cam into their actuating positions.

17. Means for use in operating electric cars and the like including devices for stopping the car and emergency devices, a handle which is movable about the axis to control the operation of the car, an auxiliary handle

40 movable relatively to said handle and having a cam shaped portion movable relatively to said axis, actuating members extending

into proximity to said axis and adapted to actuate said car stopping devices and said emergency devices and extending into proximity to said axis and to be successively 50 moved by said cam into their actuating positions, and means for yieldingly moving said auxiliary handle when released into a position to engage the actuating member for said car stopping means.

55 18. Means for use in operating electric cars and the like, including devices for stopping the car and emergency devices, a handle which is movable about an axis to control the operation of the car, an auxiliary handle movable relatively to said handle and having a cam shaped portion movable relatively to said axis, a switch member extending into the path of movement of said cam and adapted to cause the actuation of said car 60 stopping devices, said switch member being moved into actuating position by an initial movement of said auxiliary handle, and a valve opening member adapted to be engaged by said switch member upon further 65 movement thereof by said cam to cause the actuation of said emergency devices.

19. Means for use in operating electric cars and the like, including devices for stopping the car and emergency devices, means 70 for conducting motive fluid to said car stopping devices, means separate from said first mentioned means for transmitting motive fluid to said emergency devices, and a connection between said transmitting means 75 including a check valve which permits the motive fluid to flow from the last mentioned means to the first mentioned means and which resists the flow of motive fluid in the reverse direction, and a handle which when 80 released causes motive fluid to enter said first mentioned transmitting means and which upon further movement causes motive fluid to be transmitted to both of said transmitting means.

EDWARD J. FUTTERER.
